TUMBLING MACHINE

Richard E. Bogema, Sturgis, Mich., assignor to
The Grav-I-Flo Corporation, Sturgis, Mich., a
corporation of Michigan

Application January 25, 1951, Serial No. 13,978

Term of patent 14 years

(Cl. D49—1)

To all whom it may concern:

Be it known that I, Richard E. Bogema, a citizen of the United States of America, residing at Sturgis, county of St. Joseph, State of Michigan, have invented a new, original, and ornamental Design for a Tumbling Machine, of which the following is a specification, reference being had to the accompanying drawing, forming part thereof.

Figure 1 is a front perspective view of a tumbling machine embodying my new design.

Figure 2 is a rear perspective view of the machine.

Figure 3 is a side elevation of the machine.

The broken line representations are shown merely for the purpose of illustration.

I claim:

The ornamental design for a tumbling machine, as shown and described.

RICHARD E. BOGEMA.
